UNITED STATES PATENT OFFICE.

AMASA ORELUP, OF CHICAGO, ILLINOIS.

FURNACE.

SPECIFICATION forming part of Letters Patent No. 577,113, dated February 16, 1897.

Application filed December 7, 1896. Serial No. 614,736. (No model.)

To all whom it may concern:

Be it known that I, AMASA ORELUP, a citizen of the United States, residing at Chicago, in the county of Cook and State of Illinois, have 5 invented a certain new and useful Improvement in Furnaces, (Case No. 1,) of which the following is a full, clear, concise, and exact description, reference being had to the accompanying drawings, forming a part of this 10 specification.

My invention relates to furnaces, and more particularly to hot-air furnaces.

A well-known form of hot-air furnace consists of a stove in which the combustion of fuel takes place, and about which is disposed a casing of brick or galvanized sheet-iron in which the cold air is heated, flues being provided which convey the heated air to the points of application. In furnaces of this 15 character it has been customary to associate a radiating-chamber with the combustion-chamber or fire-pot and the heating-dome, the volatile products of combustion being circulated within said radiating-chamber and then 20 led to the chimney-way.

The object of my invention is to provide means for retaining the heated products of combustion for a longer period of time within the radiating-chamber, thus increasing the 25 radiating power of the furnace and effecting a considerable economy of fuel.

Generally speaking, my invention consists in so situating the outlet from the radiating-chamber that the products of combustion 30 must pass nearly or quite to the bottom of the chamber in order to escape, and the tendency of heated vapor being to rise above that which has become cooler it will be seen that the vapor that has become the coldest will be 35 the first to escape to the chimney-way, and the maximum quantity of heat will be imparted to the air for distribution with a minimum combustion of fuel.

One form of my invention will be particularly described with reference to the accompanying drawings, in which—

Figure 1 is an elevational view, partly in section, of a hot-air furnace embodying my invention. Fig. 2 is a sectional plan taken 50 on line 2 2, Fig. 1.

Similar letters of reference are used to designate similar parts in both figures.

The furnace to which I have shown my invention as applied is of that class in which gas is used for fuel, the burner *a* being disposed near the bottom of the dome or combustion-chamber *b*. A valve *a'* is provided to control the flow of gas to said burner. Concentrically disposed about the dome is an annular radiating-chamber *c*, communication 55 between the two being afforded by the enclosed passage *d*.

A partition *e* is provided in the radiating-chamber *c*, between the mouth of the passage *d* and a riser or outlet-pipe *f*, thus preventing the escape of the products of combustion 60 until they have circulated throughout the radiating-chamber. The mouth *f'* of the pipe *f* is quite near the bottom of the radiating-chamber, thereby causing the retention of the 65 heated vapor within the radiating-chamber for a considerable period of time and securing a maximum radiation of heat.

A supplemental or "direct-draft" outlet-pipe *g* is provided whose mouth is directly 70 opposite that of the passage *d*. This is to provide a direct draft in starting a fire, and is closed by the damper *g'* as soon as combustion is well under way. A damper *f''* is provided in the outlet-pipe *f* to control the 75 passage of vapor therethrough.

The outlet-pipes *f* and *g* are each connected with the pipe *h*, which leads to the chimney-way.

Cold air is admitted within the casing *i*, 80 and, passing upward, is heated by contact with the dome and radiating-chamber, being finally passed out to the points of application through the flues *k* in the usual manner.

My invention is capable of various modifications which will readily suggest themselves to those skilled in the art, and I do not therefore desire to be understood as limiting myself to the precise construction shown; but,

Having thus described my invention, what 90 I claim as new, and desire to secure by Letters Patent, is—

1. In a furnace, the combination with a combustion-chamber, of a radiating-chamber associated therewith, a passage affording 95 communication between said combustion-chamber and said radiating-chamber, and an outlet-pipe leading from said radiating-chamber to the chimney-way, the mouth of said

outlet-pipe being situated nearly or quite at the bottom of said radiating-chamber, substantially as and for the purpose described.

2. In a furnace, the combination with a 5 combustion-chamber, of an annular radiating-chamber concentrically disposed about the same, a passage affording communication between said combustion-chamber and said radiating-chamber, an outlet-pipe or riser, 10 the mouth whereof is near the bottom of said radiating-chamber, and a partition in said radiating-chamber, between said outlet-pipe and said passage communicating with the

combustion-chamber, substantially as and for the purpose specified. 15

3. The combination with the combustion-chamber *b*, of the radiating-chamber *c*, passage *d*, partition *e*, riser or outlet-pipe *f*, the direct-draft pipe *g*, and a damper *g'* therein, substantially as and for the purpose specified. 20

In witness whereof I hereunto subscribe my name this 28th day of November, A. D. 1896.

AMASA ORELUP.
